FOOD WARMING STAND

Max Fischer, Brooklyn, N.Y., assignor to American Casserole & Specialty Co., Inc., Brooklyn, N.Y., a corporation of New York

Filed Mar. 14, 1960, Ser. No. 59,721

Term of patent 3½ years

(Cl. D71—10)

FIG.3

Fig. 1 is a perspective view of a food warming stand showing my new design;

Fig. 2 is a top plan view thereof; and

Fig. 3 is an end elevation thereof.

I claim:

The ornamental design for a food warming stand, as shown.
